United States Patent Office

Des. 196,921
Patented Nov. 19, 1963

196,921

TELEPHONE HANDSET

Charles F. Mattke, Fanwood, N.J., assignor to Bell Telephone Laboratories Incorporated, New York, N.Y., a corporation of New York

Filed July 16, 1962, Ser. No. 70,943

Term of patent 14 years

(Cl. D26—14)

FIG. 3

FIG. 2

FIG. 1

FIG. 1 is a bottom plan view of a telephone handset, showing my new design;

FIG. 2 is a side elevational view, the opposite side being a mirror image thereof; and

FIG. 3 is a top plan view thereof.

The characteristic features of the design are shown in full lines.

I claim:

The ornamental design for a telephone handset, as shown and described.
